(57) CLAIM

The ornamental design for an entertainment furniture system, as shown and described.

DESCRIPTION

FIG. 1 is a front perspective view of an entertainment furniture system according to the present invention.

FIG. 2 is a rear perspective view of the system of FIG. 1. FIG. 3 is a left side view of the system of FIG. 1 showing recessed panels outlined with quarter-round bead; and, FIG. 4 is a detail view of a portion of the system of FIG. 1 indicating features typical of all doors and drawers of the system of FIG. 1 including raised half-round bead on the outermost edges of the face of each door and drawer, and quarter-round bead in contact with glazing and framed panels of each door.

The furniture system is shown in a position wherein the left and right cabinets are placed a maximum distance apart. The left and right cabinets are able to be moved into positions that place the cabinets closer together.
